UNITED STATES PATENT OFFICE.

CLARENCE HOPKINS MILLER, OF LUTON, ENGLAND, ASSIGNOR TO AKTIEBOLAGET
SVENSKA KULLAGERFABRIKEN, OF GOTTERNBOORG, SWEDEN.

ROLLER-BEARING.

1,199,404.

Specification of Letters Patent. Patented Sept. 26, 1916.

Application filed June 3, 1915. Serial No. 31,868.

To all whom it may concern:

Be it known that I, CLARENCE HOPKINS MILLER, a subject of the King of England, residing in Luton, in the county of Bedford, England, have invented certain new and useful Improvements in Roller-Bearings, of which the following is a specification.

This invention relates to improvements in roller-bearings and has for its object to provide a self-aligning roller-bearing of improved, simple and efficient construction.

The bearing according to the present invention will be capable of carrying a greater load than a ball-bearing of equal dimensions and will be able, by reason of its capacity for self alinement, to adapt itself automatically to any deflections of the shaft or incorrect alinement of the housing in which it may be fitted.

20 The type of roller bearing to which the present invention relates is that in which rollers run between two track-rings which present convex surfaces to the rollers so that point contact or substantially point contact is established between the rollers and each of the track-rings. According to the present invention, however, a roller-bearing of this type is characterized by the inner track-ring being formed with a spherical track-surface 25 for the rollers, and in one form the center of curvature of the inner track is coincident with the center of the bearing.

A feature of the invention consists in a construction of bearing in which a line joining the centers of transverse curvature of the inner and outer tracks passes through the points of contact of the rollers with those tracks.

Other features of the invention will be 40 more clearly understood with reference to the accompanying drawings, in which—

Figure 1 is a central section through one form of roller-bearing according to the present invention, and Fig. 2 is a side elevation 45 of the bearing shown in Fig. 1; Fig. 3 is a central section of a modified form of bearing, and Fig. 4 is a side elevation of the bearing shown in Fig. 3.

Referring to the bearing illustrated in 50 Figs. 1 and 2, two rows of rollers A A¹ are disposed between track-rings B and C and the rollers of the two rows are arranged either in staggered relationship as indicated

in Fig. 2 or they may be side by side as indicated in Fig. 4.

The track-ring C presents a spherical track to the rollers, its bearing surface being curved as a portion of a sphere struck from the center D of the bearing. In the illustration the outer track-ring B has an individual outer track for each roller set, the drawings show two tracks to accommodate the two rows of rollers and is divided by a central ridge-piece B¹. The rollers are substantially cylindrical so that owing to the curvature of the tracks point contact or substantially point contact is established between the rollers and the tracks. The curvature of the outer tracks is such that a line, as shown at E, radiating from the center D 70 of the bearing, passes through the points of contact of a roller and both tracks. The center of transverse curvature of each of the outer tracks is therefore situated on a line, such as E, and is indicated at F. The lines 75 E preferably also pass through the center points of the rollers.

The rollers are kept evenly spaced by fitting them in a cage floating between the inner and outer tracks B and C and indicated at G. Preferably the cage G is made in one piece formed as an annulus and slotted to receive the rollers in such a manner that they may revolve easily and with a minimum amount of friction between them 80 and the cage. The cage also facilitates the positioning of the rollers at the required angle, as illustrated in the drawings.

In Figs. 3 and 4 is illustrated a modified form of bearing in which the inner track C 90 is formed with a spherical track-surface and the outer track B is formed with two track-surfaces or race-ways, each of which is provided along its outer edges by flanges B², in addition to the central dividing flange B¹ 95 as in the outer track-ring illustrated in Fig. 1. Each row of rollers is provided with a separate cage G¹, G², each of which is suitably slotted to receive the rollers and to position them at the correct angle.

In both the cases illustrated in the drawings, the flange B¹ serves as a guide for the inner edges of the rollers, while in Fig. 3 the flanges B² act as additional guides. It will be readily understood that owing to the 105 sphericity of the inner track which is com-

mon to the two rows of rollers, the bearing is automatically self-aligning as it will operate equally satisfactorily if the inner and outer track-rings are oblique to one another, the inner track ring or member being capable of tilting relatively to the outer track ring or member and the rollers.

The rollers are capable of withstanding a greater load than balls of equal diameter and, moreover, they operate with a minimum amount of friction as substantially only point contact is maintained between them and the tracks.

The invention is not limited to the details of construction shown in the drawings as these may be varied provided always that the invention, as defined by the claims, is not departed from.

What I claim as my invention and desire 20 to secure by Letters Patent is:—

1. A roller-bearing comprising a plurality of roller-sets running between inner and outer track-members there being an individual outer track for each set formed to 25 present a convex track-surface to the rollers and an inner track-member formed with a spherical track-surface common to all the roller-sets.

2. A roller-bearing having a plurality of 30 roller-sets running between inner and outer track members there being an individual outer track for each set formed to present a convex-track surface to the rollers and an inner track-member formed with a spherical 35 track-surface common to all the roller-sets, the center of curvature of the inner track being coincident with the center of the bearing.

3. A roller-bearing having a plurality of 40 roller-sets running between inner and outer track-members there being an individual outer track for each set formed to present a convex track-surface to the rollers and an inner track-member formed with a spherical 45 track-surface common to all the sets, the construction being such that a line joining the centers of transverse curvature of the inner and outer tracks passes through the points of contact of the rollers with the 50 tracks.

4. A roller-bearing having a plurality of 55 roller-sets running between inner and outer track-members there being an individual outer track for each set formed to present a convex track-surface to the rollers and an inner track-member formed with a spherical 60 track-surface common to all the rollers, the construction being such that the center of curvature of the inner track is coincident with the center of the bearing and a line joining the centers of transverse curvature

of the inner and outer tracks passes through the points of contact of the rollers with the tracks.

5. A roller-bearing having a plurality of 65 roller-sets running between inner and outer track-members, the inner track-member being formed with a spherical track-surface and the outer track-member having an individual track surface for each roller-set 70 formed to present a convex track-surface to the rollers and having an annular rib projecting inwardly between the roller-sets.

6. A roller-bearing having a plurality of 75 roller-sets running between inner and outer track-members the inner track-member being formed with a spherical track-surface common to all the roller-sets and the outer track-member having an individual track for each set formed to present a convex 80 track-surface to the rollers and having an annular rib projecting inwardly between the roller-sets and other annular ribs projecting inwardly from the outer edges of the said track-member to overhang the outer 85 sides of the outermost roller-sets.

7. A roller-bearing having two roller-sets running between inner and outer track-members there being an individual outer track for each set formed to present a convex 90 track-surface to the rollers and an inner track-member formed with a spherical track-surface common to all the sets, the construction being such that a line joining the centers of transverse curvature of the inner and 95 outer tracks passes through the points of contact of the rollers with the tracks, an extension of such line passing through the points of contact of the diametrically opposite roller in the companion set with its 100 outer track and the spherical track.

8. A roller bearing having rollers of substantially cylindrical shape and inner and outer track members, the inner track member being formed to present a spherical 105 track surface to the rollers, whereby the said inner member may tilt relatively to the outer member and rollers.

9. A roller bearing having rollers and inner and outer track members, the outer track 110 member being formed to present a convex track to the rollers and the inner member being formed with a spherical track surface.

In testimony whereof, I have signed my 115 name to this specification in the presence of two subscribing witnesses.

CLARENCE HOPKINS MILLER.
